(57) **CLAIM**

The ornamental design for a snow blower, as shown and described.

DESCRIPTION

FIG. 1 is a top front perspective view of a snow blower showing our new design;

FIG. 2 is a top rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged view of a portion 9 shown in FIG. 1. The dot-dashed broken lines in the figures are for the purpose of illustrating from where the enlarged view is taken and form no part of the claimed design.

The dash-dot broken lines in the drawings depict the portions of the snow blower that form no part of the claimed design.
